UNITED STATES PATENT OFFICE.

CHARLES H. SHULTZ, OF ST. JOSEPH, MISSOURI.

VAPOR-BURNER.

SPECIFICATION forming part of Letters Patent No. 401,383, dated April 16, 1889.

Application filed May 16, 1887. Serial No. 238,348. (No model.)

To all whom it may concern:

Be it known that I, CHARLES H. SHULTZ, a citizen of the United States, residing at St. Joseph, in the county of Buchanan and State 5 of Missouri, have invented a new and useful Improvement in Vapor-Burners, of which the following is a specification.

My invention relates to an improvement in vapor-burners; and it consists in the peculiar 10 construction and combination of devices, as will be more fully set forth hereinafter, and particularly pointed out in the claim.

In the drawings, Figure 1 is a vertical central sectional view of a vapor-burner embodying my improvement. Fig. 2 is a horizontal 15 sectional view of the same, taken on the line *x x* of Fig. 1.

A represents a cylindrical burner-head, which has its lower side projected beyond the 20 vertical side walls, B, to form a laterally outwardly-extending portion or offset, C. The said portion or offset is hollow, as shown in Fig. 1, and communicates with the interior of the burner. The under side of the outer edge 25 of the portion or offset is rounded, as at D. This rounding of the offset is to enable the flame-jets to more readily escape over the offset and strike the sides of the vaporizing-chamber.

E represents upwardly-inclined inwardly-projecting apertures which are made in the upper side of the portion or offset C, and F represents downwardly and outwardly inclined openings which are made through the 35 lower side of the portion or offset C. Formed integrally with the burner and arranged concentrically on the same is an annular vaporizing-chamber G.

It will be observed by reference to Fig. 1 40 that the openings E are arranged at such an angle as to project the jets of flame against the outer side of the chamber G, and thereby heat the latter so intensely as to cause the oil which is fed thereto by the usual stand-pipe, H, to be instantly vaporized on coming 45 in contact with the sides of the chamber. The openings F on the lower side of the offset or portion C direct jets of flame downward and outward from the burner. The curved lower 50 side, D, of the said portion or offset causes

the jets projected from the openings F to curve upward around the said offset or portion.

I represents the vapor-pipe, which extends from the chamber G and terminates in a vertical sleeve, K, below the center of the burner. In this sleeve is located the needle-valve L.

The lower end of the vertical sleeve K is provided with screw-threads, as shown at 60 Fig. 1.

P represents a packing-gland, which is cylindrical in shape and is provided with interior screw-threads adapted to fit the threads on the lower end of the sleeve T, and has a threaded central opening in which works the 65 threaded portion of the valve. Packing material, R, is arranged in the packing-gland below the sleeve and around the lower end of the needle-valve. By turning the gland so as to cause it to be screwed upward on the 70 sleeve K the packing material may be compressed to such a degree as to absolutely prevent the escape of vapor from the lower end of the sleeve.

M represents a vertical tube, which has its 75 upper end screwed in a central opening in the bottom of the burner. The lower end of this tube M extends through a central opening in an oil-cup, N, and serves to support the latter. O represents a set-screw which connects the lower end of the tube to the oil-cup. 80

The operation of my invention will be very readily understood.

A small quantity of oil, previously placed in the cup N, is first ignited to heat the 85 burner and the chamber G, and a supply of oil is fed to the chamber G by the stand-pipe. As the oil reaches the chamber, it is vaporized by the heat and is fed through the pipe I and the sleeve K, and directed upward from 90 the latter through the tube M into the burner. As the vapor passes through the tube, air is sucked in with it and becomes commingled with the vapor in the burner, thereby rendering the same combustible by oxygenizing it. 95 As the oxygenized vapor escapes through the openings E and F, it is burned, as previously described. Particular stress is laid on the construction of the burner with the lateral offset or portion C, the top of which is perfo- 100

rated to provide the jet-openings; also, the openings F in the bottom of the burner are an important feature.

It will be understood that the packing in the gland is interposed between the tube K and the threads on the valve. Heretofore, so far as I am aware, the screw-threads on the valve have extended up past the packing. This is objectionable because the residuum in the vapor will settle on the threads and gum the latter to such an extent as to impede the working of the valve.

By my improvement the packing effectively prevents the vapor from settling on the threads of the valve.

Having thus described my invention, I claim—

The burner A, having the annular vapor-

izing-chamber G on its outer side and closed at the top, the lower side of the burner being extended laterally at the bottom beyond the outer side of the vaporizing-chamber to form a hollow projecting portion or offset, C, said offset or hollow portion being provided with the openings E in its upper side, which openings are inclined inwardly, and the mixing-tube entering the bottom of the burner, as set forth.

In testimony that I claim the foregoing as my own I have hereto affixed my signature in presence of two witnesses.

CHARLES H. SHULTZ.
